UNITED STATES PATENT OFFICE.

PETER BEGHETTI, OF SAN FRANCISCO, CALIFORNIA.

WIRE TIGHTENER AND TWISTER.

Application filed August 10, 1925. Serial No. 49,214.

To all whom it may concern:

Be it known that I, PETER BEGHETTI, a citizen of the United States, residing at the city and county of San Francisco and State 5 of California, have invented new and useful Improvements in Wire Tighteners and Twisters, of which the following is a specification.

This invention relates to tightening and 10 twisting of looped wires such as are used in tying together the wooden forms for reinforced concrete walls.

A tool for this purpose is shown in my Patent Number 1,543,491, issued June 23, 15 1925, and in my application Serial Number 14,010, filed March 9, 1925, now Patent 1, 551,457, dated August 25, 1925.

The object of the present invention is to simplify and improve the construction 20 and operation of a device of this character.

I find in the practical use of this tool that to properly twist the ends of the wires they should be engaged by a relatively broad surface projecting inwardly from the face 25 plate of the tool, so that the twist will not occur so close to the edges of the face plate as to strain the wire and cause it to break. A further feature of the present invention 30 is the use of a slotted gripping member whereby the wire can be more readily inserted.

One form which my invention may assume is exemplified in the following description and illustrated in the accompanying 35 drawings, in which—

Fig. 1 shows a perspective view of a device embodying my invention;

Fig. 2 shows a perspective view of a wooden form for concrete walls, showing 40 the device of the present invention in position for twisting the tie wires;

Fig. 3 shows a vertical sectional view through a portion of the form, with the device of the present invention shown in side 45 elevation thereon;

Fig. 4 shows a sectional view of one end of the twisting and tightening tool.

The tool of the present invention includes an arm 10 having a handle 11 at 50 one end and a wedge-shaped member 12 at the opposite end. At right angles to the wedge-shaped member is a face plate 13, and carried on the wedge-shaped member slidably 55 is a clamping loop 14. This loop is for the purpose of gripping the free ends of a looped wire 15 used for tying together the

walls 16 of a wooden form. The face plate 13 is intended to be placed against the post or studding members of the form, adjacent the projecting ends of the wires 15. The 60 free ends of the wires are then inserted between the loop 14 and the wedge-shaped member 12, the loop 14 being retracted to facilitate insertion of the wire ends. To further expedite the insertion of these wire 65 ends I form a slot 17 in the loop adjacent one end. One end of the wire can be threaded through the loop while the tool is being placed in position against the studding member and thereafter the other wire 70 end can be slipped through the slot 17 without bothering to line up the wire ends or straighten them out. The clamping loop is then moved forwardly to grip the wire 75 ends, and tightening of the wire is performed by pressing downwardly on the arm of the tool with the heel of the face plate 13 engaging the studding element.

When the wire is sufficiently tightened it is necessary to twist the free ends together; and for this purpose I provide a wing or lug 18 on the face plate 13 near the upper end thereof. This wing or lug is preferably flattened and curved as best 80 shown in Fig. 1, so that one wire end lies beneath one end of the wing and the other wire end overlies the opposite end of the wing. This wing being positioned on the face plate and having appreciable width, 85 acts to space the face plate out from the form and leave room for forming a twist without unduly straining the wire or drawing it tightly against the sharp edges of the face plate, as in my prior application above 90 referred to.

It will be seen that I have provided a tool which is strong and rugged and inexpensive to construct. In addition it is capable of faster operation and is not so liable to break 100 the wire as are the particular designs shown in my earlier applications.

Having thus described my invention, what I claim as new and desire to secure by Letters Patent is:

1. A tightener and twister for the purpose stated, comprising an arm having a gripping member at one end for engaging the free end of a wire loop, a face plate on said gripping member, and a wing or lug projecting at right angles from said face plate and positioned so that one wire end lies beneath one end of the wing and the 110

other wire end overlies the opposite end of said wing.

2. A tightener and twister for the purpose stated, comprising an arm, a wedge-shaped member on the end of the arm, a clamping loop slidably mounted on the wedge-shaped member for gripping the ends

of a tie wire, a face plate extending at right angles to the wedge-shaped member, and a flattened wing or lug extending at right angles from the face plate to engage the wire for twisting the latter.

PETER BEGHETTI.
